UNITED STATES PATENT OFFICE.

ARVID ANDERSSON LIND, OF STOCKHOLM, SWEDEN.

ROTARY ENGINE AND PUMP.

1,277,436.

Specification of Letters Patent.

Patented Sept. 3, 1918.

Application filed November 13, 1913. Serial No. 800,837.

To all whom it may concern:

Be it known that I, ARVID ANDERSSON LIND, a subject of the King of Sweden, and residing at Kungsholmsgatan 2B III, Stockholm, Sweden, have invented certain new and useful Improvements in Rotary Engines and Pumps, of which the following is a specification.

This invention has for its object an improved construction of rotary engine of the internal combustion type.

Describing the invention in somewhat general terms it consists in the provision of two circular members one of larger diameter than the other, coacting with each other and mounted eccentrically to one another so that an annular chamber of varying width is formed around the member of less diameter. The members are prevented from rotating one in relation to the other and operate either by the axis of one of them revolving about the axis of the other or by both of them rotating about their axes respectively at the same angular velocity; and means are provided whereby the chamber formed around the member of smaller diameter is divided into compartments. As the members are prevented from turning in relation to one another it follows that any point on the inner member revolves about a line passing parallel to the axes of the members and through some point which is constant of the other member.

The periphery of the member of less diameter preferably touches the inner surface of a peripheral wall of the member of larger diameter so that a somewhat crescent shaped space is formed between the two members.

The verb "to rotate" is used in the specification only in the special sense of the turning of some mass as a whole upon an axis while the verb "to revolve" is used in the sense of one mass or part thereof turning about another mass or part thereof, such as when the axis of one mass is made to revolve around the axis of another, whether there is rotation of either mass or not. It is in the same sense as the revolution of the earth about the sun.

If the members are allowed to rotate the drive would be taken from one or each of them, and the axes would not actually revolve about each other, but would be held stationary and would form an abutment for the drive. If however the members are held from rotating on their axes, then the latter

would be arranged actually to revolve about each other and the drive would be taken from the axes, the members, or at any rate one of them, acting as the abutment for the drive. The arrangement of rotating members is much preferred because their inertia can be used to steady the drive, and it is possible to obtain very perfect balancing of moving parts.

If the members touch or come closely adjacent to each other along a line, a chamber is formed between them extending from the line of contact around between the members back to the line of contact; and, if there is no line of contact, an annular chamber is formed varying in width. This chamber in either case is divided by one or more partitions formed by tongues of the one member extending into recesses in the other. Some part of each tongue is always in contact with or closely adjacent to some part of the corresponding recess to effect a closure, and as the members have no rotative movement relatively to each other, but only a movement of revolution one in relation to the other, it is always arranged that some part of each recess is caused to wipe over a curved surface of the corresponding tongue or vice versa; but the same part and curved surface may not always be in such proximity. It is however, arranged that each recess is always contacting with the corresponding tongue at some point or other though at different times it is by one part and one curved surface, and at other times by another part and another curved surface.

Preferably I arrange that while a part of a recess is wiping over a curved surface of a tongue, a part of the same tongue is also wiping over a curved surface of the recess. Thus there may be a double closure at any rate at certain times and it also allows of a very convenient arrangement of ports as will be hereinafter made clear.

Although it has been stated that there is no relative rotative movement between the members, it would be possible, as will be clearly understood hereafter, to provide that the inner member and a part of the outer member carrying tongues thereof, should rotate relatively to a peripheral portion of the outer member which might form a stationary part of the apparatus. It is not considered that such an arrangement would be convenient; but it would come within the scope of the invention.

The invention is more particularly described with reference to the drawings here-with, of which:—

Figure 1 is a sectional elevation of some-
what diagrammatic form of the drums of a
rotary internal combustion engine arranged
according to my invention.

Fig. 2 is a view corresponding to Fig. 1,
but showing the position of the drums rela-
tively to each other after they have each
turned through an angle of 90°.

Fig. 3 is a view corresponding to Fig. 1,
but showing the drums turned through an
angle of 180°.

Fig. 4 is a view corresponding to Fig. 1,
but showing the drums turned through an
angle of 270°.

Fig. 5 is a longitudinal section through
the entire engine constructed according to
this invention, taken in the plane indicated
by line 5—5 of Fig. 1.

Fig. 6 is an end view of the engine shown
by Fig. 5.

Fig. 7 is a section taken in the plane indi-
cated by line 7—7 of Fig. 4.

Fig. 8 illustrates a modification in which
the tongues are placed at right angles to
each other instead of opposite.

Fig. 9 illustrates a modification in which
four tongues and four recesses are em-
ployed.

Fig. 10 is a view to illustrate the modifi-
cation already referred to in which the
peripheral portion of the outer drum is
held stationary.

Fig. 11 is a sectional view of the same
modification, the section being taken in the
plane indicated by the line 11—11 of Fig.
10.

Referring first to Figs. 1 to 7 which illus-
trate a simple application to internal com-
bustion engines working upon a cycle anal-
ogous to that of a four stroke engine, 1 rep-
resents the outer drum having two tongues
2 and 3, oppositely disposed as shown, and
4 represents the inner drum having two re-
cesses 25 and 26 correspondingly placed.
In the back wall of the outer drum 1 (and
on the right hand side of the tongue 3 as
shown in Fig. 1) is the inlet port 7. At the
opposite side of the same tongue is the ex-
haust port 8, shown only by broken lines
because, being situated in the front wall of
the outer drum, it comes in front of the
plane in which the section is taken. The re-
cess 25 is formed somewhat larger than the
recess 26 for a purpose presently made clear,
and in communication with the recess 25,
which I will call the ignition recess, is the
sparking plug 9. The outer drum 1 is ar-
ranged to rotate about the stationary center
10 and the inner drum about the stationary
center 11. The curves at either side of each
tongue are struck with a radius equal to the
distance apart of the centers 10 and 11 plus

half the thickness of the metal at the lips
of the recesses. Likewise the curves at each
end of the recess 26 and the smaller curves
at each end of the recess 25 are struck with
a radius equal to the distance apart of the
centers 10 and 11 plus half the thickness of
the tips of the tongues. The radius of the
larger curves at the ends of the recess 25 is
greater than that of the smaller curves but
actual size of the recess can be varied to
some extent according to the amount of
compression desired. The respective inlet
and exhaust ports are opened and closed by
the movement thereover of the lips of the
recesses. 13, 13 are pins in the outer drum
passing through chambers 14, 14 in the in-
ner drum and by their interaction with the
cylindrical walls thereof, insures that both
disks rotate evenly at the same speed, and
that there is no substantial pressure be-
tween the tongues and the recesses. One or
other of the lips of each recess is always
wiping around the corresponding curve of
the corresponding tongue and likewise one
or other of the tips of each tongue 3 is al-
ways wiping around the corresponding curve
of the corresponding recess 26. Also one
or other of the tips of the tongue 2 is al-
ways wiping around the smaller curves of
the recess 25, but in doing so it will at some
positions leave a passage between itself and
the wall of the recess as shown in Figs. 2
and 4. The curve of the inner face of each
tongue is struck from the center of the
larger drum, and the inner curve of each
recess from the center of the smaller drum.

Referring specially to Figs. 5 and 6, the
drum 1 is carried upon a shaft 21 which is
supported in bearings 22, 23, of standards
24, 27, which are supported by the bed-plate
28, and the drum 4 is carried upon a shaft
29 which is supported in bearings 30, 31,
of standards 32, 33, which are supported by
the bed-plate 28. The shaft 29 is hollow
and the connections for the sparking plug 9
are carried therethrough. The shafts 21
and 29 are geared together through the me-
dium of a spur-wheel 34 of the shaft 29
which gears into a wheel 35 of a counter-
shaft 36, and of a spur-wheel 37 of the shaft
36 which gears into a spur-wheel 38
of the shaft 21.

The action of the apparatus is as fol-
lows:—Assuming the drums to be in the po-
sitions shown in Fig. 1 the mixture inlet
port 7 communicates with a chamber 15
which enlarges in size with the rotation of
the drums. In Fig. 2 this chamber 15 in-
cludes most of the recess 26 and a part of
the annulus or space between the drums and
it is still in communication with the inlet
port so that mixture is being drawn in. In
Fig. 3 the chamber 15 is seen to be still fur-
ther enlarged and to be still in communica-
tion with the inlet port. In Fig. 4 it is still
130

more enlarged but the inlet port has commenced to close. In Fig. 1 the chamber 15 has become the chamber 16, communication between it and the inlet port is cut off and the chamber is contracting in volume thus compressing the mixture. In Fig. 2 the chamber 16 is further contracted and includes very little besides the ignition recess 25. In Fig. 3 the chamber 16 includes only the ignition recess 25 and the gases are at maximum compression. At this point the gases are fired from the sparking plug. In Fig. 4 the chamber 16, which has now become the chamber 17 is seen to be expanding. At this time the burnt gases are doing work and driving the drums because they are tending to expand the chamber 17 which they can only do by the rotation of the drums. In Fig. 1 the chamber 17 is seen to have expanded further but is not yet open to the exhaust. In Fig. 2 the chamber 17 has expanded to a maximum and the exhaust is opened to the chamber. In Fig. 3 the chamber 17 has become the chamber 18 and is again contracting and sweeping the products of combustion out into the exhaust. In Fig. 4 the chamber 18 is further contracted and in Fig. 1 again is seen to consist of little more than the exhaust port. In Fig. 2 it is seen to be disappearing entirely so that all the exhaust gases are swept out. The cycle of operations has been described as beginning at Fig. 1 with the forming of the chamber 15 and the opening of the inlet port 7. As a matter of fact the cycle actually commences in Fig. 4 where the initial chamber must be designated 19 and is seen as just commencing to form and to be already open to the inlet.

It will now be understood that at each revolution of the engine there is one charge drawn in, another charge compressed, another charge ignited and allowed to expand and a fourth charge allowed to go to exhaust. It will be seen on reference to Fig. 1 that a part of the burnt gas gets trapped in the ignition recess 25 and would foul the new mixture in the chamber 16 (see Fig. 2) or possibly cause its pre-ignition. This is avoided however by a hole 20 in the rear wall of the outer drum and a hole 20^a through a shallow wall 20^b of the recess momentarily opening communication between the recess 25 and the atmosphere. The hole 20 in the rear wall of the drum is also arranged to allow the shaft of the inner drum to pass out through the said wall of the outer drum. The diameter of this hole must be twice as great as the distance between the two axes plus the thickness of the shaft of the inner drum.

A distributer 39, which consists substantially of a circular plate 40 and a rim 41, is carried by the standard 24 with the edge 65 of its rim 41 just touching the outer face

of the side plate 1^a of the member 1. Combustible mixture from the carburter or air, is drawn into this distributer through an opening 42 and is drawn from the distributer through the inlet port 7 by the interaction of the members 1 and 4. 70

The portions of the tongues have been described as wiping around the recesses and vice versa but they may be arranged so that they do not actually touch. If the coupling 75 devices consisting of the pins 13 and chambers 14 are arranged to keep the disks absolutely in phase with each other, the tips of the tongues and lips of the recesses may sweep so close to their respective curved surfaces that they may make a sufficiently good joint although there is no appreciable friction between them. 80

It will be seen from the above description that there is no actual or relative reciprocal 85 movement between the drums but only a movement of revolution of each point of the inner drum about a line passing parallel to the axes and through some corresponding point of the other drum. Consequently the 90 wear between the drums is very equally spread. Also there is no actual reciprocatory movement at all and when the axes are stationary and the drums revolve, there is no actual movement of revolution of one 95 part about another, but the whole movement is of rotation about two stationary axes. All the parts are therefore in perfect balance.

As will be understood air only may be 100 drawn into the drums and the fuel separately injected, as is usually the case in large internal combustion engines.

Referring next to Fig. 8, there is there illustrated a modification in which the 105 tongues and recesses are disposed at 90° to each other. The working of the apparatus is the same as that of the previous figures except that the firing and exhaust chambers are larger than the suction and compression 110 chambers.

Fig. 9 has four tongues and four recesses with two sparking plugs and ignition chambers. The working is very much the same as in the previous figures but everything is 115 duplicated. For instance there are two explosions to each revolution.

It may here be pointed out that the action of the various engines described above is easily followed by forming templets or outline models to represent the inner drums cut out in accordance with the drawings. In using such a templet there is no necessity to rotate it and the outer drum but simply to revolve the axis of the templet around that 125 of the outer drum carefully keeping both the outer drum and the templet from rotating on their own axes.

Figs. 10 and 11 illustrate the modification before mentioned in which while the inner 130

drum revolves and also the tongues and a side wall or walls of the outer drum, yet the peripheral portion of the outer drum is held stationary. As will be understood, however, 5 such an arrangement is a fairly obvious alternative to the form shown in Figs. 1 to 7.

As will be seen in all the modifications the revolving surfaces, which move over one another, do so always in the same direction 10 and at the same angular velocity whereby the inconveniences due to such surfaces reciprocating in relation to one another is avoided.

If the tongues and recesses are kept from 15 actual contact by the action of the coupling devices, there will be some leak past them, but it may be arranged so that it is quite inconsiderable especially when the engine is rotating at a high speed. If a fairly thick 20 oil is used, as may be the case owing to the relatively small movement between the parts, it may serve to make a joint to a greater or less extent. If the tongues and recesses are kept out of contact there will be no friction 25 between them which, as will be readily understood may, especially at high speed, more than compensate for loss by leakage.

The ports have been described as opening in the side walls of the larger drum, but as 30 will be obvious they might be arranged in the peripheral wall.

In all the modifications the tongues are carried by the outer member and the recesses formed in the inner; but as will be 35 clear the reverse arrangement might be adopted.

It is not essential that the two drums shall be geared together by spur gearing if they are otherwise geared together such as by the 40 pins 13 operating within openings 14 as described; but even when the two drums are geared together by spur wheels it is preferred to gear them also such as by pins 13 operating within openings 14.

45 Instead of the exhaust being allowed to go straight out to the atmosphere, it might be collected in a stationary exhaust box similar to the inlet box before mentioned.

I claim:

50 1. In a rotary internal combustion engine the combination of two members which are geared to rotate in the same direction at the same angular velocity, one being of larger diameter than and mounted eccentrically 55 to the other and adapted to perform eccentric movements in relation to the other, a space between the two members formed by the interaction of such members into which space fluid is drawn and then compressed by 60 the contraction of such space by the continued interaction of the members, the compressed fluid transferred to a further space which is formed between the members by the continued interaction thereof, fired therein 65 and expanded during the expansion of such

space, and inlet and outlet ports which are common to a plurality of said projections and recesses.

2. In a rotary internal combustion engine, the combination of two members one of 70 larger diameter than and mounted eccentrically to the other and adapted to perform eccentric movements in relation to the other, said members having projections and recesses, the projections of one member operating within the recesses respectively of the other member with a movement of revolution therein as distinct from rotation, said projections and recesses having curved surfaces which wipe over one another by relative movement between the members, compression and expansion spaces between the members which are closed by said projections and recesses and alternately expand and contract as the members move relatively 75 to one another, each projection operating only within the recess to which it constantly corresponds, one or more of said recesses adapted to interact in succession with a compression space between the members and an expansion space between such members, the combustible mixture being fired within such recess, and a port from such recess, which is controlled by the interaction of said members and opened momentarily to allow escape 80 of burnt gas from such recess.

3. In a rotary internal combustion engine, the combination of two members one of larger diameter than and mounted eccentrically to the other and adapted to perform 100 eccentric movements in relation to the other, said members having projections and recesses, the projections of one member operating within the recesses respectively of the other member with a movement of revolution therein as distinct from rotation, said projections and recesses having curved surfaces which wipe over one another by relative movement between the members, compression and expansion spaces between the members which are closed by said projections and recesses and alternately expand and contract as the members move relatively 105 to one another, each projection operating only within the recess to which it constantly corresponds and one or more of said recesses adapted to interact in succession with a compression space between the members and the expansion space between such members the combustible mixture being fired within such 110 recess.

4. In a rotary internal combustion engine the combination of two members one of larger diameter than and mounted eccentrically to the other and adapted to perform 125 eccentric movements in relation to the other, said members having projections and recesses, the projections of one member operating within the recesses respectively of the other member with a movement of revolution 130

tion therein as distinct from rotation, said projections and recesses having curved surfaces which wipe over one another by relative movement between the members, compression and expansion spaces between the members which are closed by said projections and recesses and alternately expand and contract as the members move relatively to one another, each projection operating only within the recess to which it constantly corresponds, and one or more of said recesses adapted to interact in succession with a compression space between the members and an expansion space between such members, the combustible mixture being fired within such recess and said recess formed to provide a passage which places the ends of the recess in constant communication with each other.

5. In a rotary internal combustion engine the combination of two members one of larger diameter than and mounted eccentrically to the other and adapted to perform eccentric movements in relation to the other, said members having projections and recesses, the projections of one member operating within the recesses respectively of the other member with a movement of revolution therein as distinct from rotation, said projections and recesses having curved surfaces which wipe over one another by relative movement between the members, compression and expansion spaces between the members which are closed by said projections and recesses and alternately expand and contract as the members move relatively to one another, each projection operating only within the recess to which it constantly corresponds, one of said recesses communicating in succession with a compression space and an expansion space, an ignition device for the combustible mixture within such recess and a passage between the ends of the recess.

6. In a rotary internal combustion engine the combination of two members one of larger diameter than and mounted eccentrically to the other and adapted to perform eccentric movements in relation to the other, said members having projections and recesses, the projections of one member operating within the recesses respectively of the other member with a movement of revolution therein as distinct from rotation, said projections and recesses having curved surfaces which wipe over one another by relative movement between the members, compression and expansion spaces between the members which are closed by said projections and recesses and alternately expand and contract as the members move relatively to one another, each projection

operating only within the recess to which it constantly corresponds, one or more of said recesses adapted to communicate in succession with a compression space between the members and the expansion space between such members, the combustible mixture being fired within such recess, said recess formed to provide a passage which places the ends of the recess in constant communication with each other, and said passage provided by the ends and bottom of the interior of the said recess being of a size which always leaves a clearance space between them and said projection, said projection contacting with said recess only at the edges of the mouth thereof.

7. In a rotary internal combustion engine the combination of two members one of larger diameter than and mounted eccentrically to the other and adapted to perform eccentric movements in relation to the other, said members having projections and recesses, the projections of one member operating within the recesses respectively of the other member with a movement of revolution therein as distinct from rotation, said projections and recesses having curved surfaces which wipe over one another by relative movement between the members, and compression and expansion spaces between the members which are closed by said projections and recesses and alternately expand and contract as the members move relatively to one another, each projection operating only within the recess to which it constantly corresponds, one or more of said recesses adapted to communicate in succession with a compression space between the members and an expansion space between such members, the combustible mixture being fired within such recess, said recess formed to provide a passage which places the ends of the recess in constant communication with each other, said passage provided by the ends and bottom of the interior of the said recess being of a size which always leaves a clearance space between them and said projection, said projection contacting with said recess only at the edges of the mouth thereof, and inlet and outlet ports which are common to a plurality of said projections and recesses.

In witness whereof I have hereunto signed by name this 30th day of October, 1913, in the presence of two subscribing witnesses.

ARVID ANDERSSON LIND.
